Primary Examiner — Austin Murphy(74) Attorney, Agent, or Firm — Schultz & Associates, P.C.CLAIM

The ornamental design for a pant rack, as shown and described.

DESCRIPTION

FIG. 1 is a perspective view of a pant rack showing my new design;

FIG. 2 is a front elevation view thereof;

FIG. 3 is a side elevation view thereof; and,

FIG. 4 is a top view thereof.

The broken lines shown represent unclaimed subject matter and form no part of the claimed design.
